US00D961081S

(12) **United States Design Patent** (10) Patent No.: **US D961,081 S**
 Sayger et al. (45) Date of Patent: **** Aug. 16, 2022**

(54) **ORTHOPEDIC IMPLANT**

(71) Applicant: **CROSSROADS EXTREMITY SYSTEMS, LLC**, Memphis, TN (US)
 (72) Inventors: **Daniel Sayger**, Southaven, MS (US);
Michael Chad Hollis, Collierville, TN (US);
Vernon R. Hartdegen, Collierville, TN (US)

(73) Assignee: **CROSSROADS EXTREMITY SYSTEMS, LLC**, Memphis, TN (US)

(**) Term: **15 Years**

(21) Appl. No.: **29/758,800**

(22) Filed: **Nov. 18, 2020**

(51) LOC (13) Cl. **24-03**

(52) U.S. Cl.

USPC **D24/155**
